UNITED STATES PATENT OFFICE.

ALBERT E. FROMMEL, OF GROTON, SOUTH DAKOTA.

GRAIN GRADER AND CLEANER.

Application filed August 19, 1921. Serial No. 493,516.

To all whom it may concern:

Be it known that I, ALBERT E. FROMMEL, a citizen of the United States, residing at Groton, in the county of Brown and State 5 of South Dakota, have invented certain new and useful Improvements in Grain Graders and Cleaners; and I do hereby declare the following to be a full, clear, and exact description of the invention, such as will enable 10 others skilled in the art to which it appertains to make and use the same.

This invention relates to new and useful improvements in grain graders and cleaners and has for its primary object the provision 15 of means for forming grain in a sheet or curtain form past the air blast of the device and which is capable of adjustment to vary the amount of grain in the curtain and is so constructed that the chances of the grain 20 clogging is entirely obviated.

Another object of this invention is the provision of an adjustable combined dividing wing and chute located below the curtain forming means to separate and catch the 25 desired grain from the chaff and other foreign matter and to direct said grain to a receptacle or the like.

Another object of this invention is the provision of a blast control adapted to automatically regulate the air to the fan as the latter decreases and increases in speed to 30 keep a predetermined air blast from the fan at all times.

A further object of this invention is the provision of a grain grader and cleaner of the above stated character, which will be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:

Figure 1 is a side elevation, illustrating a grain grader and cleaner constructed in accordance with my invention,

Figure 2 is a vertical sectional view illustrating the same,

Figure 3 is a detail sectional view illustrating an automatic blast control,

Figure 4 is a detail sectional view illustrating the curtain forming hopper,

Figure 5 is a sectional view taken at right angles to Figure 4 and illustrating the adjustable front wall of the curtain forming hopper,

Figure 6 is a plan view illustrating the combined grading wing and collecting chute.

Referring in detail to the drawings, the numeral 1 indicates a main supporting frame carrying at its upper end a grain receiving hopper 2 adapted to discharge grain into an inclined trough 3. The trough 3 is supported by hangers 4 and is capable of oscillatory movement, and has located at its upper portion, a screen 5 for the purpose of separating dust, dirt and like foreign matter from the grain, and said foreign matter escapes from the trough 3 by way of a discharge chute 6. The grain passes from the screen 5 onto a scalping sieve 7 of any desired construction and which separates from the grain chaff and other foreign matter and the grain falls through the scalping sieve 80 onto the bottom wall 8 of the trough and escapes from the trough by way of an opening 9. The scalping sieve 7 extends beyond the opening 9 for the purpose of directing chaff and other foreign matter onto an extension 10 formed on the lower end of the trough 3 so as to deposit said foreign matter in a pile on the ground or into a suitable receptacle. The trough 3 is mounted for reciprocation and receives its movement by 85 means of a pitman 11 connected to an eccentric on a drive shaft 12. The drive shaft 12 may be rotated in any suitable manner and is equipped with a pulley over which an endless belt 13 travels and said belt is also trained over a pulley on a fan shaft 14. The fan shaft is supported by longitudinally extending beams 15 and carries a fan 16 located within a fan casing 17. The sides of the casing 17 are partially open to permit the fan to receive air and the air is discharged through a pipe 18 on the casing and which terminates in a plane below and inwardly of the lower end of the trough 3. A curtain forming hopper 19 is carried by the supporting structure 1 below the opening 9 and above the discharge end of the air blast pipe 18 and includes a rear wall 20 having an upper inclined portion 21 and a lower vertically disposed portion 22. The hopper 19 also includes side walls 23 that project beyond the discharge end of the air blast pipe

18 and slidably supports a front wall 24. The front wall 24 has reduced screw threaded portions slidably mounted in slots 25 formed in the side walls and said reduced screw threaded portions have wing nuts 26 turned thereon for the purpose of clamping the front wall against movement and also at various distances from the rear wall. The grain after passing through the scalping 10 sieve 7 passes through the opening 9 into the curtain forming hopper and falls out of the same in sheet form and in front of the discharge end of the air blast 18 so that small and light grain will be blown away from the 15 heavy or desired grain which falls directly down past the air blast pipe and is caught in a combined grading wing and collecting chute.

The combined grading wing and collecting chute includes end walls 17' and 18' connected by side walls 19' and an inclined bottom wall 20'. The end wall 18' adjacent its lower edge is provided with a discharge opening or slot 21 to permit grain sliding 25 down the inclined bottom wall to be caught within a discharge chute 22'. The end wall 17' is adapted to form a dividing wing and located in such a manner that the graded grain will fall onto the inclined bottom 20' 30 while the lighter grain and chaff and other foreign matter will be directed beyond the same with the aid of the air blast. The discharge chute 22' may be inclined so that the graded grain may slide into a suitable receptacle placed thereunder. The combined grading wing and collecting chute is provided with a frame 23' slidably mounted in guides 24' on the main frame 1 and said frame 23' is reinforced by diagonally extending truss rods 25'. By having the frame 23' slidably mounted on the main frame this permits the location of the wall 17' to be varied in respect to the curtain of grain falling from the hopper 19 in front of the discharge end of the air blast 18. This device is especially adapted for cleaning and grading wheat which usually contains other seeds, such as oats, timothy and the like. The wheat is larger and heavier than the 50 other seeds mentioned and when discharged from the curtain forming hopper, the wheat falls directly downwardly and is not interrupted in its fall by the air blast, but the lighter grain is caught by the air blast and blown to one side of the machine. The front wall of the grain forming hopper being adjustable permits the amount of grain discharged from the curtain forming hopper to be varied.

60 The fan casing 17 has hinged to its sides, gates 27 which have connected thereto arms 28. The arms 28 have angularly related portions 29 and 30. The portions 30 are secured to the gates while the portions 29 are adapted to normally contact with the

sides of the fan casing under the influence of a tension spring 31 connected to the free ends of the arms 28 by cables or flexible elements 32. As the speed of the fan increases, the suction of air increases accordingly which will draw the gates 27 to a closed position or in a position closing the openings in the sides of the casing 17 and cut off a part of the air supply. As the gates 27 move towards a closing position 70 they tension the spring 31 and as the speed of the fan decreases, the gates 27 are moved towards an open position by means of said spring, thus it will be noted that means has been provided to permit a predetermined 80 amount of air blast from the fan at all times.

While I have shown and described the preferred embodiment of my invention, it will be understood that minor changes in 85 construction, combination, and arrangement of parts may be made without departing from the spirit and scope of the invention as claimed.

90 What is claimed is:—

1. In combination, a grain cleaner and grader including a main frame supporting an air blast and a scalping sieve, a curtain forming hopper receiving the grain from said sieve, an auxiliary frame slidably mounted on the main frame to permit adjustment thereof relative to the curtain forming hopper, and a combined dividing wing and grain collector carried by the auxiliary frame and adapted to catch the 95 graded and cleaned grain after passing the air blast.

2. In combination, a grain cleaner and grader including a main frame supporting an air blast and a sieve, a curtain forming 105 hopper receiving grain from said sieve, an auxiliary frame adjustably mounted on the main frame, a receptacle carried by the auxiliary frame and having an inclined bottom, and a discharge opening, one end wall 110 of said receptacle adapted to form a dividing wing, and a discharge chute receiving grain from said receptacle.

3. A grain grader and cleaner including a supporting structure and a hopper, a 115 cleaning mechanism associated with said hopper, an air blast, means carried by the supporting structure, a curtain forming hopper carried by the supporting structure including rear, side and front walls, said rear walls having an inclined portion and a vertical portion, means adjustably securing the front wall to the side walls for the purpose of adjusting the front wall towards and from the rear wall to vary the size 120 of the curtain of grain discharged from the curtain forming hopper, and means receiving the grain after passing the air blast.

4. A grain grader and cleaner comprising a supporting structure, a hopper carried by 130

said structure, a trough carried by said structure, means for reciprocating the trough, a screen carried by the trough, a discharge chute for the screen, a scalping sieve carried by the trough, said trough having an opening to permit the grain passing through the scalping sieve to discharge from the trough, an air blast means carried by the structure, a curtain forming hopper receiving grain from said opening and deliver-

ing the grain in advance of the air blast means, and means catching the grain from the curtain forming hopper after passing the air blast means.

In testimony whereof I affix my signature 15
in presence of two witnesses.

ALBERT E. FROMMEL.
